UNITED STATES PATENT OFFICE

PHILIP KAPLAN, OF BROOKLYN, NEW YORK, ASSIGNOR TO THE DEHYDRO COMPANY,
OF TULSA, OKLAHOMA, A CORPORATION OF OKLAHOMA

MEDIUM FOR DEHYDRATING CUT OILS

No Drawing.

Application filed April 22, 1931. Serial No. 532,127.

In the dehydrating of cut oils I have discovered that it is desirable to produce a medium for accomplishing this purpose that shall have certain desirable and I might say 5 necessary qualifications. The medium should be miscible in water and should have such affinity for the water that even a small quantity of the medium will take up or cause the ingathering of all of the water in the cut oil 10 emulsion or solution and it is therefore necessary that the material be added to the cut oil either as an emulsion or that it become immediately emulsifiable therein and the material should also be miscible in petroleum so 15 as to mix freely therewith and break the bond or surface tension which exists between the oil and water in the cut oil emulsion.

To operate most successfully a dehydrating compound must have a very low freezing 20 point so that it will remain fluid in all temperatures to which cut oil emulsions are subjected and I believe that in the product that I am about to describe I have discovered an emulsion breaker that meets all requirements far better than emulsion breakers so 25 far produced.

My material consists of sulphonated linseed oil and I fully realize the difficulties encountered in sulphonating linseed oil, the 30 primary difficulty of which is the viscous nature of the mass in certain steps of the operation, in fact it has been found that linseed oil will actually ball up or form itself into a gelatinous mass when under the necessary 35 temperature conditions concentrated sulphuric acid is added thereto and to overcome this great difficulty I have found it desirable to add to the linseed oil a solvent such as carbon tetrachloride or one of the 40 chloroform group or one of the benzine group, or possibly turpentine, adding this solvent prior to sulphonation and later removing the solvent or the excess portions thereof by distillation or by other means, the removal only 45 taking place however after sulphonation is completed.

Sulphonated linseed oil, like other sulphonated oils is soluble in water, but I believe that in the use of this material in cut oil emulsions it is desirable to introduce it into the

cut oil as an emulsion and therefore I may add a quantity of raw linseed oil to the sulphonated linseed oil and thereafter add water to complete the emulsion, but I have found by experimentation that because of the low 55 temperature at which linseed oil will flow that linseed oil may be employed with other sulphonated or unsulphonated mixtures now used for the treatment of cut oils and the addition of such will reduce the temperature 60 at which the treating material becomes inoperative and therefore I may use linseed oil as a dilutant for other mixtures and as a substitute for pine oil, rosin oil, or benzine, all of which are employed for the purpose of 65 assuring fluidity at low temperatures.

In completing a cut oil treating agent as such I may add linseed oil to mineral oil or fish oil or other vegetable oils. I have found that it is desirable to sulphonate to the highest possible degree although in some so-called free water emulsions sulphonated linseed oil may be mixed with other raw oils, with or without the addition of water to complete the emulsion and in so-called tight emulsions 75 the water may be omitted from my mixture either wholly or in part, thus increasing the penetration of the mixture and causing it to complete its emulsification by taking up the water from the cut oil mixture.

It is my belief that the art of sulphonating oils is sufficiently well understood to make it unnecessary for me to describe this operation in detail, except to say that it is desirable and I consider it necessary to add a solvent to the 80 oil to make the sulphonation commercially possible. To what extent this solvent will be removed will of course be determined by the desires relative to the nature of the final product.

I believe that the use of cut oil emulsion breakers is sufficiently well understood to make it unnecessary for me to describe in detail the use of my material and of course at this time it is not possible to suggest all of 85 its uses or the nature thereof. However, having carefully described my invention, what I claim and desire to secure by Letters Patent is:

1. A material for separating water and oil 100

emulsions comprising sulphonated linseed oil and raw linseed oil.

2. A material for separating water and oil emulsions comprising sulphonated linseed oil,
5 a relatively small amount of a retained solvent and raw linseed oil.

PHILIP KAPLAN.
